UNITED STATES PATENT OFFICE.

ARTHUR H. SKAER AND EDWIN J. DOWNING, OF DENVER, COLORADO, ASSIGNEES TO THE DENVER ROCK DRILL MANUFACTURING COMPANY, OF DENVER, COLORADO, A CORPORATION OF DELAWARE.

LUBRICATOR FOR WINDING DRUMS.

Application filed July 13, 1926. Serial No. 122,108.

The present invention relates more particularly to means that will insure the proper lubrication of a winding drum or like rotatable object.

5 One of the objects is to provide a simple structure that will be effective, irrespective of the conditions under which the drum is operated. That is to say, it has been found from actual experience that the temperatures 10 vary greatly and difficulty has been experienced in providing a lubricating means that will insure the lubrication of the drum bearing under such varying temperature conditions. The structure disclosed in the accompanying drawings and hereinafter described has been found to give highly satisfactory results under such conditions.

15 A further and incidental object is to provide means whereby the cable or other article 20 that wraps upon the drum will also be supplied with lubricant.

In the accompanying drawings:

Figure 1 is a vertical longitudinal sectional view through a known type of double drum hoist, the drums thereof being equipped with the lubricating means constituting the subject-matter of the present invention.

25 Figure 2 is a sectional view through the hub portion of one of the drums removed 30 from its mounting.

Figure 3 is a sectional view taken substantially on the line 3—3 of Figure 2.

Figure 4 is an end elevation of the hub portion of another drum.

35 In the embodiment disclosed, a suitable supporting structure 5 is provided, in which is journaled a shaft 6 shown as driven by a worm gearing 7. On this shaft and on opposite sides of the worm gearing are loosely 40 journaled drums 8. Each drum may be clutched to the shaft, clutching mechanism for one of the drums being shown generally at 9.

45 Considering each specific drum, it consists of a shell having a hub portion 10 with flanges 11. The hub portion is chambered, as illustrated at 12 and 13, and a sleeve 14 is fitted into the drum shell and constitutes a bearing member that rotates on the shaft 6, 50 this shell constituting the inner walls of the chambers 12 and 13. One of the chambers is considerably larger than the other and constitutes a lubricant container or reservoir. Access is gained to it through an opening

closed by a removable plug 15. The sleeve is 55 provided with an internal longitudinal oil groove 16, terminating short of the outer end of said sleeve and opening through the opposite or inner end. A radial groove 17, cut in the inner end of the drum shell and the 60 sleeve 14, is in communication with the groove 16, as will be clear by reference to Figure 4. The lubricant chamber 12 is substantially filled with oil absorbing material, such as felt or waste, said material being 65 designated 18. Preferably, however, at the filling port 15 this material is cut away, as shown at 19 in Figure 3 to form a pocket to receive the oil poured into the chamber, which oil is thus absorbed by the material 70 18. Furthermore wicks 20 extend through the shell 14, these wicks being preferably embedded in the material 18 and have their inner ends at different points on the interior of the shell 14, so that they will rub against 75 different portions of the shaft 6. One of the wicks, as clearly illustrated in Figure 2, intersects the internal groove 16.

As heretofore stated, the radial groove 17 is cut in the inner end of the drum. The opposite end of the groove 16 has a port 21 opening into the other chamber 13. This chamber 13 has a further port 22 that opens through the exterior of the drum hub. The outer end of the shell 14 beyond the port 21 is 80 preferably provided with an internal groove 23 containing a ring 24 of felt that serves to prevent the passage of oil along the shaft to the clutch surfaces of the clutch mechanism 9.

85 It has been found that grease is unsatisfactory for lubricating structures of this character, because it is either too hard in cool temperatures, or becomes too fluid when warmed by the atmosphere and the heat generated in the operation of the structure. The arrangement, disclosed, however, has been found to make oil highly effective as the lubricant, the oil being fed by capillary attraction to the drum bearings, and any excess being delivered outwardly through the passageway formed by the ports 21 and 22 and the chamber 13 so that the cable is oiled. At the same time oil is prevented 95 passing on to the friction surfaces of the clutch mechanism, partly by the stop ring 23 and partly because it has an outlet through the ports 21 and 22.

From the foregoing, it is thought that the construction, operation and many advantages of the herein described invention will be apparent to those skilled in the art, without further description and it will be understood that various changes in the size, shape, proportion and minor details of construction may be resorted to without departing from the spirit or sacrificing any of the advantages of the invention.

What we claim, is:

1. The combination with a shaft, of a winding drum journaled thereon and having a lubricant holding chamber, means for delivering lubricant from the chamber to the shaft and means for directing a portion of the lubricant delivered to the shaft to the exterior of the drum to lubricate the cable wrapped on the drum.
2. The combination with a shaft, of a winding drum journaled thereon and having a lubricant holding chamber, and means for delivering lubricant from the chamber to the shaft, and a passageway through the drum from the shaft to the exterior of the drum to deliver lubricant from the shaft

and drum to the cable wrapped on the drum.

3. The combination with a shaft, of a winding drum journaled thereon and having a lubricant holding chamber, and an internal groove, a wick extending from the chamber to the groove, and a passageway from the internal groove to the exterior of the drum to deliver lubricant from the groove to the cable wrapped on the drum.

4. The combination with a shaft, of a winding drum journaled thereon and having an internal lubricant chamber and lubricant absorbing material in the chamber, said drum having an internal groove, wicks from the chamber to the bore of the drum, one of said wicks intersecting the groove, said drum having a groove in one end that is in communication with one end of the internal groove, and a passageway from the other end of the internal groove to the exterior of the drum.

In testimony whereof, we affix our signatures.

ARTHUR H. SKAER.
EDWIN J. DOWNING.
